UNITED STATES PATENT OFFICE.

ARVID GERHARD DAMM, OF RONNINGE, SWEDEN.

APPARATUS FOR DECRYPTING CIPHER MESSAGES.

Application filed August 29, 1924, Serial No. 734,904, and in Sweden September 10, 1923.

This invention relates to an improved apparatus for deciphering cipher messages and more particularly to a combination of the apparatus described in the Creed British Patent Nr. 164,370 and known as the Creed printer and the apparatus described in my U. S. Patent Nr. 1,540,107, dated June 2, 1925.

The object of my invention is to render it possible to decipher automatically telegrams which have been enciphered by means of my said apparatus, herebelow called the electrocryptographer.

The essential feature of my invention resides in this that the selector arms of the Creed printer, which according to the patent effect the stopping of the writing or type wheel in the desired positions, are arranged to actuate electric contacts in circuits which according as the reversing switch of the electrocryptographer is in the one position or the other will pass through or past the commutator members or ciphering cylinders of the electrocryptographer and in which are inserted electromagnets adapted to actuate moveable members so as to bring the same into the path of the stop arm of the type wheel of the Creed printer for stopping said wheel in the desired positions.

In the accompanying drawing I have shown one embodiment of my invention. Fig. 1 is a diagram showing the electric connections of the apparatus and Fig. 2 is a vertical longitudinal section of the Creed printer, illustrating the alterations and additions embodying the present invention. Fig. 3 is a perspective view of a Creed printer many of the details being omitted as they are not necessary to a complete understanding of the present invention.

As is shown in Fig. 2 the writing or type wheel *a* of the Creed printer is disposed in such manner, that the stop arm *b* thereof cannot be reached by the selector arms *V₁₀*. The latter have each a radially directed portion *10c* adapted to actuate the moveable member of a contact *k_{10t}* which will be closed when the corresponding selector arm *V₁₀* is turned by its spring *10d*. The contacts *k_{10t}* are, as will be more particularly described herebelow, arranged to close the circuits of electromagnets *Mt*, mounted on the inner side of a stationary ring *43*. The

number of contacts *k_{10t}* and electromagnets *Mt* corresponds to the number of selector arms. The ring *43* is formed with an inwardly extending flange *43a* having radial grooves *43b*, in which angle levers *44* are swingably journaled, said levers being by means of springs *46* kept in such a position, that they are not in the path of the stop arm *b* of type wheel *a*. The outwardly swinging movement of the angle levers is limited by pins *47* inserted in said levers and striking the sides of the flange *43a*. The number of angle levers *44* corresponds to the number of electromagnets *Mt*, and each angle lever is provided with an armature *44a* by means of which it can be actuated by the respective electromagnet *Mt*. When an angle lever is turned by an electromagnet it will place itself in the path of the stop arm *b* of the type wheel *a* and stop said type wheel, whereupon the hammer *21* actuates the corresponding type arm *k* and a print is obtained on the paper band fed between the type wheel and the platen *n*. The turning of the selector arm *V₁₀* is, as well known, effected by a band which is fed into the Creed printer and is perforated in accordance with the signs in the arriving telegrams. A telegram written by the electrocryptographer consists of the following parts:

a. An unciphered group of signs, indicating the position of the key mechanisms at the end of the preceding telegram;

b. Address and ordinary service remarks in clear text with the usual division in words or corresponding groups of signs;

c. The telegram proper in cipher, divided into groups of an equal number of signs, for instance five, and comprising complete groups only; and

d. An information in clear text of the number of cipher groups contained in the telegram.

In order to make an automatic deciphering of such a telegram practicable, the telegram must contain special signs, herebelow called shift signs, which are not enciphered and effect an automatic reversion of the switch of the electrocryptographer, which adjusts the electrocryptographer for the rendering of clear text or for deciphering. When a telegram received is to be de-

ciphered, after the adjustment of the ciphering cylinders and the key disks into the initial positions stated in the telegram, said positions corresponding to the initial positions of the corresponding members of the electrocryptographer, by which the telegram has been enciphered, and after the adjustment of the aforesaid switch W, (Fig. 1) for the rendering of clear text in the telegram (the position shown by dash lines in Fig. 1) and also after the adjustment of a switch Q (Fig. 1), described herebelow, for automatic deciphering, the operations of deciphering the telegram will be as follows.

By the adjustment of the switch Q for automatic deciphering the circuit of the motor E is closed, said motor driving the Creed printer. This circuit is as follows: from the positive pole of the source of current S through the conductor 49, contacts Q₁ and Q₂ of the switch Q, conductor 50, motor E, conductor 51, contact k_p, the function of which will be described herebelow, and conductor 52 to the negative pole of the source of current S.

The first sign on the perforated band fed into the Creed printer, which sign is part of a clear text, causes the selector arm V₁₀ corresponding to said sign to be turned and close its contact k_{10t}. Hereby the following circuits (Fig. 1) are closed.

(a) From the positive pole of the source of current S through conductor 49, contacts Q₁ and Q₂ of the switch Q, conductor 50, conductor 94, contacts W₁₃ and W₁₁ of the switch W, conductor 96, a commutator ap described herebelow, conductor 91, contact k_{10t}, conductor 92, conductor 78t, contacts W₁ and W₅ of the switch W, conductor 83, contacts Q₁₀, Q₁₁ of the switch Q, conductor 83a, conductor 93t, the electromagnet Mm corresponding to the actuated selector arm V₁₀ of the Creed printer, and conductor 52 to the negative pole of the source of current S.

(b) From the positive pole of the source of current to the contact k_{10t} the same way as under (a) and thereafter through conductor 92, conductor 98, conductor 66, conductor 65, solenoids S₄, S₅ and, according as one or more of the contacts k₅, k₆, k₇, k₈ actuated by the key disks N₁, N₂, N₃, N₄ are closed through one or more of the conductors 55, 54, 56, 57, 58 and 62, 61, 59, 60 respectively, through one or more of the contacts f₁, f₂, f₃, f₄ of the secondary key V₅, conductor 53, conductor 68, contacts Q₄, Q₅ of the switch Q and conductor 70 back to the negative pole of the source of current S.

(c) The same way as under (b) up to and including conductor 66, and therefrom through conductors 67, the parallelly connected solenoids S₁, S₂, S₃ and S₄, conductors 68¹ and conductor 68, switch con-

tacts Q₄, Q₅, and conductor 70 back to the negative pole of the source of current S.

The circuit described under (a) effects the stopping of the type wheel a of the Creed printer in such a position that the type arm k, corresponding to the selector arm actuated and thus to the first sign of the telegram, is actuated by the hammer 21 (Fig. 2) and prints said sign on the paper band fed between the type wheel a and the platen n. 75

The circuit described under (b) effects a turning of one or both of the ciphering cylinders C₁, C₂.

The circuit described under (c) effects a turning of the key disks N₁, N₂, N₃, N₄. 80

The same operations will be repeated for each sign of the clear text of the telegram. The empty spaces on the perforated band fed into the Creed printer, which spaces correspond to the spaces between the words of the clear text of the telegram, effect the actuating of a selector arm marked V_{10m} in Fig. 1. When this selector arm is turned, it breaks a contact k_{10c} and closes a contact k_{10m} and thereby completes the following circuit: from the positive pole of the source of current S through conductor 49, switch contacts Q₁, Q₂, conductor 50, conductor 94, switch contacts W₁₃, W₁₁, conductor 96, commutator ap, conductor 91b, switch contacts W₁₄, W₁₅, conductor 77, contact k_{10m}, conductor 95, switch contacts W₁₆, W₁₇, conductor 93m, electromagnet Mm and conductor 52 back to the negative pole of the source of current S. Hereby the electromagnet Mm actuates an angle lever 44m, which arrests the type wheel of the Creed printer in such a position that a space between the two words is obtained in the telegram typed by the Creed printer. 105

Upon the clear text of the telegram follows a shift sign, the purpose of which is to effect a re-adjustment of the electrocryptographer from clear text to deciphering. This shift sign effects the turning of a selector arm V_{10w} of the Creed printer, whereupon the corresponding contact k_{10t} closes the following circuit: from the positive pole of the source of current S through conductor 49, switch contacts Q₁, Q₂, conductor 50, conductor 94, switch contacts W₁₃, W₁₁, conductor 96, commutator ap, conductor 91a, contacts k_{10t}, conductor 99, electromagnet S_w, conductor 100 and conductor 52 back to the negative pole of the source of current. 115 The electromagnet S_w now actuates a reversing device L_w (diagrammatically indicated in Fig. 1) operating the switch W, so that the latter is re-adjusted to the position shown in full lines in Fig. 1. 120

Now, when the first cipher sign of the telegram causes a turning of the corresponding selector arm of the Creed printer, the contact k_{10t} actuated by said selector arm closes the following circuits: 125

(d) From the positive pole of the source of current S through conductor 49, switch contacts Q_1 , Q_2 , conductor 50, conductor 50b, a commutator a_2 , described below, conductor 90, commutator ap , conductor 91, the contact $k_{10}t$ corresponding to the selector arm actuated, conductor 92, conductor 78t, switch contacts W_1 , W_2 , conductor 76, contact k_3t , ciphering cylinders C_1 , C_2 , contact k_4t , conductor 75, switch contacts Q_7 , Q_8 , conductor 93t, an electromagnet Mt and conductor 52 back to the negative pole of the source of current S.

(e) From the positive pole of the source of current S the same way as under (d) up to and including contact $k_{10}t$ and therefrom through conductor 92, conductor 98, conductor 66, conductor 65, solenoids S_4 , S_5 , and according as one or more of the contacts k_5 , k_6 , k_7 , k_8 actuated by the key disks N_1 , N_2 , N_3 , N_4 are closed, through one or more of the conductors 55, 54, 56, 57, 58 and 62, 61, 59, 60 respectively, one or more of the contacts f_1 , f_2 , f_3 , f_4 of the secondary key V_5 , conductor 53, conductor 68, contacts Q_4 , Q_5 and conductor 70 back to the negative pole of the source of current S.

(f) From the positive pole of the source of current S the same way as under (e) up to and including conductor 66, therefrom through conductors 67, the parallelly connected solenoids S_{31} , S_{32} , S_{33} and S_{34} , conductors 68¹ and conductor 68, switch contacts Q_4 , Q_5 , and conductor 70 back to the negative pole of the source of current S.

The circuit described under (d) passes through the electromagnet Mt , corresponding to that sign of the original telegram text, which is rendered by the first cipher sign of the telegram received. The circuit described under (e) causes one or both of the ciphering cylinders C_1 , C_2 to be turned. The circuit described under (f) causes the key disks N_1 , N_2 , N_3 , N_4 to be turned.

The circuit described under (d) consequently causes a deciphering of the first cipher sign of the telegram. That a correct deciphering is obtained, provided the telegram text received be correctly rendered on the perforated band fed into the Creed printer, is evident from the fact that the ciphering cylinders C_1 , C_2 and the key disks N_1 , N_2 , N_3 , N_4 have been turned in exactly the same manner as the corresponding members of the electrocryptographer by which the telegram has originally been written while the Creed printer is rendering the clear text of the telegram.

For every following sign on the perforated band fed into the Creed printer, and corresponding to a cipher sign, the operations just described will be repeated. When five subsequent signs have been deciphered, there follows on the perforated band an empty space corresponding to the space between

two groups of signs of the telegram arrived. This empty space causes, as above described, the selector arm $V_{10}m$ of the Creed printer to be turned and breaks the contact k_{10c} and closes the contact k_{10m} . The function of these two contacts will be described herebelow.

During the production of the cipher by the electrocryptographer said spaces between groups of signs were obtained automatically, without any special adjustment of the ciphering cylinders and the key mechanisms.

During the deciphering of the telegram it is, consequently, necessary that, while each space between groups of signs is passing through the Creed printer, the circuits above mentioned under (e) and (f) are disconnected, which is performed by the above mentioned commutator a_2 described herebelow.

Upon the ciphered part of the telegram follows a shift sign causing selector arm $V_{10}x$ to be turned, whereby the following circuit is closed:

From the positive pole of the source of current through conductor 49, contacts Q_1 and Q_2 , conductor 50, conductor 50b, commutator a_2 , conductor 90, commutator ap , conductor 91a, contact $k_{10}t$, conductor 99, electromagnet S_w , conductor 100, conductor 52 to the negative pole of the source of current. Hereby the electromagnet S_w is re-excited, whereby the reversing device L_k is actuated and re-adjusts the switch W for clear text. The last part of the telegram, containing—in clear text—an information of the number of groups of cipher signs, is thereupon rendered by the Creed printer exactly as above described concerning the rendering of the first part of the telegram.

As above mentioned the telegram received appears in the shape of a paper band with Morse-signs, rendered in the commonly known way by perforations. By occasional deficiency in the mechanical functions of the apparatus, by which the perforated bands are produced, or, in wireless telegraphy, also on account of atmospheric disturbances, whole signs or parts thereof may disappear, and in such cases it may also occur that a combined sign is divided into two or more shorter signs.

The ciphered part of the telegram, which originally contained groups of five signs, may thus contain groups of a greater or smaller number of signs than five.

The electrocryptographer, however, effects a turning of the keys for every sign enciphered or deciphered, and a necessary condition for obtaining a correct deciphering is that the electrocryptographer prior to the enciphering or deciphering of the same sign, has effected an equal number of such turnings. Therefore, if any sign is lost or added, that synchronism is broken and must be restored, if the sequence shall be correct.

This purpose is served by the arresting device which is built upon co-operation between the commutators a_1 and a_2 , diagrammatically shown in Fig. 1, the selector arm 5 for empty spaces $V_{10}m$, the contacts $k_{10}c$ and $k_{10}m$, the electromagnet M_k and the contact kp actuated thereby.

This arresting device will be in function as long as the switch W is adjusted for deciphering and arrest the Creed printer and thereby also the electrocryptographer as soon as any fault in the successive division into five-sign-groups influences the selector-device of the Creed printer. The circumferences of 10 the commutators a_1 and a_2 , which are both driven from the driving axle 2 of the Creed-printer with such a ratio of gear, that they rotate one revolution while said axle rotates six revolutions, are divided into electrically 15 conducting and non-conducting portions in such manner that one sixth of the circumference of a_1 and five sixths of the circumference of a_2 are electrically conducting, while the other portions are non-conducting a_1 and 20 a_2 are so adjusted in relation to each other that the circuit through a_1 is closed while the circuit through a_2 is broken and so that this 25 occurs exactly at the moments when empty spaces between groups on the perforated band are passing.

If for reasons above-mentioned a space has occurred so that a group of too small a number of signs has been formed, the consequence will be that, when said space actuates 35 the selector device of the Creed printer, the selector arm $v_{10}m$ for the empty space is turned, whereby the following circuit is closed. From the positive pole of the source of current through conductor 49, contacts 40 Q_1 and Q_2 , conductor 50, conductor 50 b , commutator a_2 , conductor 90, conductor 96, contacts W_{11} and W_{12} , conductor 97, contact $k_{10}m$, conductor 88, contacts W_{18} and W_{19} , conductor 89, electromagnet M_k and conductor 45 52 to the negative pole of the source of current.

Hereby the electromagnet M_k is excited and actuates contact kp so that the same is broken, whereby the circuit for the motor of 50 the Creed printer is broken and the letter and consequently the Creed printer are stopped. The switch Q must then be readjusted for manual deciphering (the position shown by dash lines) and thereafter the 55 number of signs missing in the complete group are pressed down by hand on the key-board of the electrocryptographer. Then the perforated band is moved by hand to next empty space, whereupon the apparatus 60 is ready to continue its work.

If, on the other side, such a fault occurs in the grouping, that one group happens to contain too many signs, the circuit is closed through the commutator a_1 , when the sixth 65 sign of the group actuates the selector device

of the Creed printer. This circuit is the following one: from the positive pole of the source of current through conductor 49, conductor 50, conductor 50 a , commutator a_1 , conductor 87, contact $k_{10}c$, conductor 88, contacts W_{18} and W_{19} , conductor 89, electromagnet M_k and conductor 52 to the negative pole of the source of current. Hereby 70 the electromagnet M_k is excited and actuates the contact kp , so that the circuit of the motor of the Creed printer is broken, whereupon the motor and, consequently, also the Creed printer are stopped. The perforated band in this case must be moved by hand to the next empty space, whereupon the apparatus 75 is ready to continue its work.

In order to indicate after the Creed printer has stopped wherein the fault consists and how many signs of a group have passed the commutator a_1 is furnished with an index 80 and a dial graduated 0-5. If the index stops on 0, this indicates that the group has contained too many signs, but if the dial stops on any of the other figures, said figure indicates the number of adjustments the electrocryptographer has already effected in respect 85 of the group in question. From the above mentioned it appears that the commutator a_2 when spaces between groups are passing the 90 Creed printer breaks also the circuits described above under (e) and (f), whereby 95 turnings of the ciphering cylinders and key mechanisms are avoided.

In the Creed printer the paper band on which the telegram is produced is given one 100 feeding step for every revolution of the driving axle. In the present case the feeding movement of this band therefore must be arrested every time a space between two groups passes in deciphering, in order that 105 the clear text obtained may not be divided into equivalent groups. How this is effected appears from the device shown diagrammatically at H in Fig. 1. The pawl α for the feeding of the band is formed with an armature, which is actuated by an electromagnet 110 M_h , secured to a swingable angle arm y on which the pawl α is journalled. As long as the electromagnet M_h is excited, the pawl is 115 kept in engagement with the ratchet wheel and will thus in each rocking movement of the angle arm y turn the ratchet wheel one 120 step; but as soon as the excitation ceases, the pawl is disengaged by the influence of a spiral spring z on account whereof the rocking movement of the angle lever will not cause the ratchet wheel to be turned.

The circuit in which the electromagnet is included is the following one: from the positive pole of the source of current through conductor 49, contacts Q_1 , Q_2 , conductor 50, conductor 50 b , commutator a_2 , conductor 101, electromagnet M_h , conductor 102 and conductor 52 to the negative pole of the source of current. This circuit according to the 125 130

above is broken by the commutator a_2 only in instances when spaces between groups of signs are passing, and in such cases consequently also the feeding of the paper band is arrested.

In the above has been mentioned a commutator ap diagrammatically shown in Fig. 1. This commutator, which is connected to the circuits of the contacts $k_{10}t$ is adapted to prevent the formation of sparks in these contacts and therefore it is so dimensioned and adjusted that it closes the circuit only the moment after the respective contact $k_{10}t$ has been closed and breaks the circuit somewhat before the respective contact $k_{10}t$ is broken. Consequently, the contacts $k_{10}t$ are currentless during the moments of time when they are closed or broken wherefore no formation of sparks can be caused in the same.

The commutator ap is placed on the driving axle of the Creed printer said axle determining the sequence of time of the different functions of the apparatus.

If for any reason the Creed printer be out of gear so that an automatic deciphering would be made impossible for the time being, the deciphering can be continued manually. The switch Q in such case is reversed to its position for manual deciphering which is shown by dash lines in Fig. 1, and when the ciphering cylinders and the key disks have been adjusted into the initial positions indicated in the telegram and the switch W has been adjusted for the rendering of clear text, viz, to the position shown by dash lines in Fig. 1, that key of key-board of electrocryptographer is pressed down which carries the first sign of the telegram, said sign being a part of clear text. Hereby the following circuits are closed:

(g) From the positive pole of the source of current through conductor 49, contacts Q_1, Q_3 , conductors 66, 72, solenoid S_2x , conductors 84, 83b, contacts Q_{12}, Q_{10} , conductor 83, contacts W_5, W_{11} , conductor 78t, contact spring k_1t , member St and conductors 80t, 70 to the negative pole of the source of current.

(h) From the positive pole of the source of current through conductor 49, contacts Q_1, Q_3 , conductors 66, 81, solenoid S_1t , conductors 82t, 78t, contact spring k_1t , member St and conductors 80t, 70 to the negative pole of the source of current.

(i) From the positive pole of the source of current through conductor 49, contacts Q_1, Q_3 , conductors 66, 65, solenoids S_4, S_5 , and according as one or more of the contacts k_5, k_6, k_7, k_8 actuated by the key disks N_1, N_2, N_3, N_4 are closed through one or more of conductors 55, 54, 56, 57, 58 and 62, 61, 59, 60 respectively, through one or more of the contacts f_1, f_2, f_3, f_4 of the secondary key v_5 , conductors 53, 68, 79m, contact spring k_2m , member Sm and conductors 80m, 70 to the negative pole of the source of current. This circuit effects a turning of

Q_4, Q_6 conductor 79t, contact spring k_2t , member St and conductors 80t, 70 to the negative pole of the source of current.

(j) From the positive pole of the source of current through conductor 49, contacts Q_1, Q_3 , conductors 65 and 67, the parallelly connected solenoids S_81, S_82, S_83, S_84 , conductors 68¹, 68, contacts Q_4, Q_6 , conductor 79t, contact spring k_2t , member St and conductors 80t, 70 to the negative pole of the source of current.

When the circuit described under (g) is closed, the solenoid s_2x of that key of the cipher-typewriter is excited, which carries the same sign as the key depressed in the key-board of the electrocryptographer.

When circuit described under (h) is closed, the solenoid S_1t is excited and actuates that key of the copy-typewriter, which carries the same sign as the key depressed in the key-board of the electrocryptographer.

The circuit described under (i) effects a turning of one or both of the ciphering cylinders C_1, C_2 .

The circuit described under (j) effects a turning of the key disks N_1, N_2, N_3, N_4 .

The same operation is repeated for every sign of the clear text of the telegram.

At the spaces between words of the clear text the key Tm of the key-board of the electrocryptographer is depressed, whereby the following circuits are closed:

(k) From the positive pole of the source of current through conductor 49, contacts Q_1, Q_3 , conductors 66, 72, conductor 73m, 100 solenoid S_2m , conductor 86, contacts W_6, W_2 , conductor 78m, contact spring k_1m , member Sm and conductors 80m, 70 to the negative pole of the source of current. By the excitation of the solenoid S_2m the spacing key of the cipher-typewriter is actuated.

(l) From the positive pole of the source of current through conductor 49, contacts Q_1, Q_3 , conductors 66, 81, solenoid S_1m , 110 conductors 82a, 78m, contact spring k_1m , member Sm and conductors 80m, 70 to the negative pole of the source of current. By the excitation of the solenoid S_1m , which actuates the spacing key of the copy-typewriter, the spaces between words are obtained in the copy.

(m) From the positive pole of the source of current through conductor 49, contacts Q_1, Q_3 , conductors 66, 65, solenoids S_4, S_5 , 120 and, according as one or more of the contacts k_5, k_6, k_7, k_8 actuated by the key disks N_1, N_2, N_3, N_4 are closed, through one or more of conductors 55, 54, 56, 57, 58 and 62, 61, 59, 60 respectively through one or more of the contacts f_1, f_2, f_3, f_4 of the secondary key v_5 , conductors 53, 68, 79m, contact spring k_2m , member Sm and conductors 80m, 70 to the negative pole of the source of current. This circuit effects a turning of

one or both of the ciphering cylinders C_1 , C_2 .
 (n) From the positive pole of the source of current through conductor 49, contacts Q_1 , Q_3 , conductors 66 and 67, the parallelly connected solenoids S_{s1} , S_{s2} , S_{s3} , S_{s4} , conductors 68¹ 68, 79^m, contact spring k_2m , member S_m and conductors 80^m, 70 to the negative pole of the source of current. This circuit causes the key disks N_1 , N_2 , N_3 , N_4 to be turned.

When the first, unciphered part of the telegram has been dealt with as described above, the switch W is reversed to deciphering position as indicated in full lines in Fig. 1. That key of the key-board of the electrocryptographer which carries the same sign as the first cipher sign of the telegram is depressed, whereby the following circuits are closed:

(o) From the positive pole of the source of current through conductor 49, contacts Q_1 , Q_3 , conductors 66, 72, 73^t, solenoid S_{st} , conductor 74, contacts Q_5 , Q_7 , conductor 75, contact k_4t , ciphering cylinders C_2 , C_1 , contact k_3t , conductor 76, contacts W_2 , W_1 , conductor 78^t, contact spring k_1t , member S_t and conductors 80^t, 70 to the negative pole of the source of current. When this circuit is closed, the solenoid S_{st} is excited and actuates the key of the cipher-typewriter corresponding to that sign of the original telegram, which has been rendered by the first cipher sign of the telegram received. This circuit consequently effects a deciphering of the first cipher sign of the telegram. Beside this circuit the circuits described under (h), (i) and (j) are closed, whereby the sign is obtained on the copy-typewriter and the ciphering cylinders C_1 , C_2 and the key disks N_1 , N_2 , N_3 , N_4 are turned. For every following sign of the telegram corresponding to a cipher sign the described operation is repeated.

The device for the adjustment of cylinders C_1 , C_2 into their initial position is the same as described in my copending application Serial Nr. 540,234 and the circuit for same is in this case the following one:

From the positive pole of the source of current through conductor 49, contacts Q_1 , Q_3 , conductors 66 and 65, solenoids S_4 , S_5 , conductors 61, 62, 63 and conductor 55, contacts k_9 and k_{10} , conductors 64, contacts f_6 and f_8 , disks O_1 and O_2 respectively, contacts f_5 and f_7 , conductor 71, contacts W_{10} , W_4 , conductors 69 and 70 to the negative pole of the source of current.

Having now described my invention, what I claim is:

1. The combination with a printing mechanism of the character specified having se-

lector arms, a printing wheel and a stop arm for said wheel, and an electro-cryptographic mechanism comprising a reversing switch and ciphering cylinders; of an electric contact pertaining to each selector arm, said contacts closing circuits through or past said cylinders, an electro-magnet in each circuit and a movable member for each magnet, which member when actuated is placed in the path of said stop-arm to selectively stop said wheel.

2. A combination as set forth in claim 1, in which one of the selector arms of the printing mechanism, which is adapted to be influenced by a so called shift sign of the telegram to be deciphered, is arranged to close the circuit of an electromagnet arranged to actuate by means of a reversing device the reversing switch of the electrocryptographer, substantially as and for the purpose set forth.

3. A combination as set forth in claim 1, in which two commutators driven by the driving axle of the printing mechanism rotate one sixth of a revolution for each whole revolution of the said driving axle, one sixth of the circumference of the one of said commutators being electrically conducting and the other five sixths being non-conducting, while five sixths of the circumference of the other commutator are electrically conducting and the remaining sixth is non-conducting, the said commutators being so adjusted in relation to each other and to the printing mechanism that the circuit through the first mentioned commutator is closed each time a space on the perforated band fed into said mechanism passes the selector device of the latter at the same time as the circuit through the other commutator is broken, the circuits of the commutators including an electromagnet which when excited breaks a contact in the circuit of the motor driving said mechanism each of said circuits including also one contact, said contacts being arranged to be actuated by the selector arm of the printing mechanism which is adapted to effect spaces in the telegram being written in such a manner that said selector arm when in idle position keeps the contact in the circuit of the first mentioned commutator closed and the contact in the circuit of the other commutator broken but when it is actuated by the selector device of the printing mechanism breaks the first mentioned contact and closes the other, substantially as and from the purpose set forth.

In testimony whereof I have hereunto subscribed my name.

ARVID GERHARD DAMM.
